UNITED STATES PATENT OFFICE.

WILLIAM L. POFFENBARGER, OF ST. LOUIS, MISSOURI, ASSIGNOR TO PYRAFORM BOTTLE MANUFACTURING COMPANY, A CORPORATION OF MISSOURI.

PAPER CONTAINER.

1,103,374.

Specification of Letters Patent.

Patented July 14, 1914.

Application filed October 5, 1903. Serial No. 456,209.

To all whom it may concern:

Be it known that I, WILLIAM L. POFFENBARGER, a citizen of the United States, and resident of St. Louis, Missouri, have invented certain new and useful Improvements in Paper Containers, of which the following is a specification.

My invention relates to improvements in paper containers which has for its object 10 to provide a container constructed of paper, substantially conoidal in form, and whose closure is effected by flattening the mouth of the container.

In the drawings—Figure 1 is a front elevation of a container embodying my invention, showing a portion broken away. Fig. 2 is a rear elevation of the same, showing the lower portion in transverse section. Fig. 3 is a side elevation of the upper portion 20 of the container. Fig. 4 is a transverse vertical view in section of the upper portion of the container.

As shown in the drawings, the main body of the container of my invention is conoidal in form and is constructed of a single sheet of paper, indicated by the numeral 5, the vertical meeting edges of which are overlapped and secured together by means of vertical parallel rows of stitching 6 and 7. 25 At the lower and larger mouth of the body section thus formed, I employ a bottom of the form shown in section in Fig. 2, having the depending circular flange 9 which is secured to the body member by means of the parallel horizontal rows of stitching 10 and 11. Between the vertical rows of stitching 6 and 7 a metallic stiffening member 12 is inserted, its upper end extending to the plane of the upper mouth of the body 35 section. The container thus formed, prior to its filling, is of the form illustrated in Fig. 1. When the contents has been placed within the container, the mouth of the body section is closed by being flattened, and the 40 mouth is then bent over upon itself in the manner illustrated in Figs. 2, 3 and 4; the metallic stiffening member 12 serving to hold the mouth closed. The rigidity of the metallic member 12 suffices to keep the 45 mouth of the container closed for ordinary purposes of trade.

Where it is desired, however, to seal the closure to prevent the intentional removal of the contents, I provide the sealing device illustrated in Fig. 2; perforations 13

and 14 being made through the upper end of the container, and the cord 15 being inserted through the perforations 13 and 14 and its free ends sealed by means of the metallic seal 16. Such form of sealing is peculiarly adapted to use of the container as a receptacle for milk or other food products, where it is desired to give the ultimate consumer the assurance that the contents have not been tampered with during their transmission from the producer to the consumer.

Where the container is used in distributing products only in bulk by the dealers and sold direct to the ultimate consumer, 70 the closure indicated in Fig. 2 by the numeral 17 will be made by flattening the walls of the body section upon itself and folding over the flattened portion thus formed at any desired point which will leave 75 the closure at a plane above the level of the contents of the container; thus, the container having a capacity of one pint is employed in the sale of a one-half pint of merchandise; the closures 17 will be at a 80 point proportionately lower than the point illustrated in Fig. 2, to suffice to leave comparatively little air space above the level of the contents.

Having fully described my invention, what 85 I claim as new and desire to have secured to me by the grant of Letters Patent, is:

1. As a new article of manufacture, a paper bottle whose side walls are formed of a single blank cut to form a truncated cone, 90 the meeting edges of said blank being overlapped and stitched together, said bottle having a circular bottom member fitted in the larger end of the bottle and provided with a downturned annular marginal flange 95 which is secured to said side walls by stitching, the bottle so constructed being treated to make the paper impervious to moisture and the seams watertight.

2. As a new article of manufacture, a 100 paper bottle whose side walls are formed of a single blank cut to form a truncated cone, the meeting edges of said blank being stitched together, said bottle having a circular bottom provided with a downturned 105 circumferential flange which is secured by stitching to the side walls of the bottle, the bottle so constructed being treated to make the paper impervious to moisture and the seams watertight, the open end portion of 110

the bottle being adapted to be folded to seal the bottle.

3. In a paper container, the combination of a conoidal body formed from a single sheet of paper whose meeting edges are secured by two or more parallel and vertical lines of stitching; a bottom member secured in place at the lower end of the body member by means of one or more lines of stitching; the mouth of the body member being folded over upon itself to form a flat closure and sealing devices extending through said closure, substantially as described.

4. In a paper container, the combination of a conoidal body formed from a single sheet of paper whose meeting edges are secured in place by two or more parallel and vertical lines of stitching; a flanged bottom member secured in place at the lower mouth of the body member by means of one or more lines of stitching passing through the flange and the body member; a metallic stiffening member mounted between the

meeting edges of the body member and between two of said parallel and vertical lines of stitching, and adapted to be bent over upon itself when the mouth of the body member is flattened, to form a closure, substantially as described.

5. As a new article of manufacture, a truncated conical bottle constructed of water-proofed paper, whose side walls are formed of a single blank cut to form a truncated cone, the meeting edges of said blank being secured water tight together by non-adhesive means, said bottle having a closed bottom in its flaring end, and the open end portion of the bottle being adapted to be collapsed and folded to form a closure.

In testimony whereof, I have signed my name to this specification, in presence of two subscribing witnesses.

WILLIAM L. POFFENBARGER.
